UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

CONTAINER TOP.

Application filed April 27, 1921. Serial No. 464,833.

To all whom it may concern:

Be it known that I, FREDERICK COATES, a citizen of the United States, residing at Cincinnati, in the county of Hamilton and 5 State of Ohio, have invented certain new and useful Improvements in Container Tops, of which the following is a specification.

This invention relates to paper containers commonly known as paper cans.

More particularly the invention relates to container tops and means of sealing the same to the can body.

It is common in the art for heads on 15 tops for cans of various materials which heads have the central portion "bumped" inward so that a U-shaped channel is provided around the head wherein the upper edge of the can body fits. It is also common in the art to coat the outside of the 20 lip or top of the body, in paper cans, with an adhesive. In metallic cans the adhesive is replaced by a solder at this point. In all such cases the inner surface of the body 25 is uncoated and consequently a capillary crack exists between the inside of the can body and the inner leg of the U-shaped channel. As a result the can contents get into this crack and, in the course of storage, 30 dry out so that it frequently happens that the contents are spoiled or are reduced in quality to such an extent as to make them unsalable.

The principal object of the present invention is to provide a paper container top which is so secured to the container body as to do away with this capillary crack and the objections pertaining thereto.

With the above and other objects in view, 40 as will be hereinafter apparent, the invention consists in general of an improved arrangement of paper container and top therefor.

In the accompanying drawings, like 45 characters of reference indicate like parts in the several views, and:—

Figure 1 is a perspective view of the container top removed from the body.

Figure 2 is a section through such a top 50 and the upper part of the body before final sealing.

Figure 3 is a view similar to Figure 2 after final sealing.

From the accompanying drawings it will 55 be seen that the improved container top

consists of a central disk-like portion 10 carrying an inverted U-shaped peripheral portion 11, the inner and outer legs of the U normally flaring before application as shown in Figures 1 and 2. Moreover the inner leg of the U is perpendicular to the body 10. The entire inside of this channel is coated with glue as shown at 12, it being understood that the term "glue" includes any suitable adhesive. After coating the inside of the channel in this way the container top is placed on the can 13. The inside leg of the channel will then bear against the inside of the body 13 at its mouth so that this inside leg will have a stratum of glue impressed between it and the body 13. The outside leg is then crimped down as shown in Figure 3. Thus there will be a stratum of glue between the body 13 and the entire inside of the channel so that there is no chance of any of the contents of the can to obtain access to the space between the container top and the body.

There has thus been provided a simple 80 and efficient device of the kind described and for the purpose specified.

Having thus described the invention, what is claimed as new, is:—

A paper container top consisting of a flat central disk like portion provided with an upstanding peripheral portion of inverted U-shape, the inner leg of said U being perpendicular to the disk like portion and the outer leg flaring downwardly and outwardly from the inner leg, the inner surface of said channel being coated throughout with adhesive; in combination with a cylindrical container closed at one end and open at the other, said cap being fitted in the open end of said container with the inner leg projecting downwardly therein, the container having a mouth fitting closely on said inner leg of the peripheral portion and thereby forcing excess adhesive 100 upwardly on said inner leg, said cap having the outer leg of said peripheral portion initially flaring outwardly from the container and being pressed against the container from above downwardly thereby expelling excess adhesive downwardly from between said outer leg and cap.

In testimony whereof I affix my signature.

FREDERICK COATES.
